UNITED STATES PATENT OFFICE.

CONRAD DIETZ, OF WEST COVINGTON, KENTUCKY.

DESIGN FOR A CASING FOR WASHING-MACHINES.

SPECIFICATION forming part of Design No. 25,623, dated June 9, 1896.

Application filed April 11, 1896. Serial No. 587,227. Term of patent 14 years.

To all whom it may concern:

- Be it known that I, CONRAD DIETZ, a citizen of the United States, residing at West Covington, in the county of Kenton, State of Kentucky, have invented and produced a novel and original Design for Washing-Machine Casings, of which the following is a specification, reference being had to the accompanying drawings, forming part thereof.
- 10 Figure 1 is a perspective view of a washing-machine casing, consisting of the body and cover attached thereto. Fig. 2 is a longitudinal vertical section of the same, taken through the center from front to rear.
- 15 My design consists in a washing-machine casing of the configuration substantially as set forth.
- 20 The lower contour of the body A is semi-cylindrical in shape, having flat parallel sides, said body having a box extension *a* at the front end near its top, substantially as shown.

The cover B has a flat four-cornered top surface and flat parallel sides whose top edges are shorter than their lower edges. The ends of the cover have flat surfaces inclining downwardly and outwardly from the top surface, the lower edges of the cover fitting to and matching the upper edges of the body A, less the front-end box extension *a* described. The upper surface of the cover has a hinged lid *b* with a longitudinal recess *b'* therein and in the central part of the cover and a recess *b²* at the rear end of said cover and lid, substantially as shown.

I claim—

25 The design for the casing for a washing-machine, substantially as set forth.

CONRAD DIETZ.
